(57) **CLAIM**

I claim the ornamental design for a water cooler for a water purifier in a sink, as shown and described.

DESCRIPTION

FIG. 1 is a perspective view of a water cooler for a water purifier in a sink

FIG. 2 is a front view thereof

FIG. 3 is a left side view thereof; and,

FIG. 4 is a top plan view thereof.

The broken line showing of the water cooler for a water purifier in a sink in FIGS. 2 and 3 is for the purpose of illustration and forms no part of the claimed design.

1 Claim, 4 Drawing Sheets

FIG. 1

FIG. 2

FIG. 3

FIG. 4
